UNITED STATES PATENT OFFICE.

LOUIS C. FOX, OF STEVENSON, WASHINGTON.

TYPE-WRITER HOLDER.

1,059,856.

Specification of Letters Patent. Patented Apr. 22, 1913.

Application filed July 25, 1912. Serial No. 711,432.

To all whom it may concern:

Be it known that I, LOUIS C. FOX, a citizen of the United States, and a resident of Stevenson, in the county of Skamania and 5 State of Washington, have invented a new and Improved Type-Writer Holder, of which the following is a full, clear, and exact description.

This invention relates to adjustable supports or brackets, and has particular reference to a device of this character adapted for supporting a typewriting machine upon a table or desk so that it may be swung around or housed out of the way when not 15 in use.

The object of this invention is to cheapen and simplify this class of devices, and at the same time make them more convenient and reliable in actual operation.

20 The foregoing and other objects of the invention are attained by means of the mechanism hereinafter fully described and claimed and illustrated in the accompanying drawings, in which—

25 Figure 1 is a perspective view of the invention shown as attached to the corner of a table or desk; Fig. 2 is a vertical sectional detail of the bracket support; and Fig. 3 is a detail in elevation of the mechanism 30 for locking the bracket upon the frame.

In carrying this invention into practice, in a preferred embodiment thereof, I indicate at 10 a frame of any suitable outline and construction, but shown as comprising 35 vertical posts 11 and 12 connected by any suitable transverse arms or bars 13 and 14. The post 11 is connected to the desk D by means of lugs 15 in vertical alinement with each other, and thereby constitutes a vertical 40 axis for the frame 10. The frame, therefore, being located at a corner of the desk structure, is adapted to swing around through an angle of substantially 270°.

The bracket 16 comprises a substantially 45 vertical standard 17 from the upper portion of which there branch pairs of arms 18 and 19, the inner ends of the arms being connected to the standard in vertical spaced relation and their outer ends extending into 50 substantially the same horizontal plane and there terminating in cups 20 or other suitable means for positive connection with the usual types of typewriting machines indicated at M in dotted lines in Fig. 1. The

bracket, therefore, is of the maximum 55 strength considering the amount of material of which it is composed and is unusually neat in appearance.

The bracket standard 17 is adjustable vertically in or through the tubular frame 60 post 12 and is adapted to be sustained in any vertical position of adjustment by a locking device shown herein as comprising a dog 21 pivoted at 21^a on the outside of said post 12 and having its nose projecting through a 65 slot 12^a in the wall of the post and into engagement with any one of a series of notches 17^a of said standard. I may journal the post 12 in the vertically alined sleeves 70 13^a and 14^a of the frame cross bars and connect to the upper end of said post 12 a collar or flange 22 having a series of notches 22^a into any one of which notches a bolt 23 is adapted to be snapped and held by a 75 spring 24, said bolt and spring being housed within a sleeve 25 clamped to the bar 13. The standard 17 is conveniently formed polygonal and is slidable vertically through 80 corresponding holes in said collar 22 and a collar 26 within the post 12, whereby the 85 bracket will be sustained in a substantially stable position within the hollow cylindrical post 12. The lower end of the post 12 has connected to it a nut 27 which prevents displacement of the post from the frame cross 90 bar 14 and the said post is prevented from downward displacement by the collar 22. It will appear, therefore, that the bracket 16 may be adjusted up or down and secured in 95 such position by means of the dog 21 independently of the rotation of the bracket and the means 23 for preventing said rotation.

The several parts of the device may be made of any suitable materials and the relative sizes and proportions thereof and also 95 the specific details of construction may be varied to a considerable extent without departing from the spirit of the invention.

Having thus described my invention, what I claim as new and desire to secure by 100 Letters Patent is:

In a device of the character set forth, the combination of a frame including a pair of bars having vertically alined end sleeves and a tubular post journaled in said sleeves, 105 means to prevent said post from being displaced upwardly with respect to the sleeves, a bracket adjustable vertically in said post

and including a polygonal standard, a collar connected to the upper end of said post and having a polygonal hole in which said standard is operative, the said collar preventing downward displacement of said post, and means coöoperating with said collar to control the rotation of said post.

In testimony whereof I have signed my name to this specification in the presence of two subscribing witnesses.

LOUIS C. FOX.
